CONTROL

Kemper P. Brace, South Bend, Ind., assignor to
 International Engineering Corporation, Chi-
 cago, Ill., a corporation of Illinois

Application August 21, 1936, Serial No. 97,102

2 Claims. (Cl. 200—140)

This invention relates to controls, and is illus-
 trated as embodied in a thermostatically-actuated
 mechanism for operating a switch or the
 equivalent.

5 An object of the invention is to provide a sen-
 sitive operating mechanism which can easily be
 adjusted. It is difficult to adjust control mecha-
 nisms of this type when they are actuated by the
 10 expansion of a fluid against the inherent resist-
 ance of a metallic bellows on which the fluid
 acts, such adjustments involving changes in the
 mounting of the bellows, and being affected by
 different characteristics of different bellows. It
 15 is extremely difficult to make such bellows with
 characteristics which are even approximately
 uniform.

According to the present invention, a lever or
 the like which actuates the switch is engaged by
 20 a metallic expandible chamber (such as a wafer
 made up by uniting the margins of two metal
 disks) which is deliberately made up to have
 relatively little resilience.

The yielding resistance is supplied by means
 such as a leaf spring secured to and extending
 25 from the end of the lever. This spring is flexed
 by the expanding fluid against a stop such as a
 setscrew adjustably threaded into a bracket or
 the like adjacent the end of the spring. The
 30 device is readily adjusted by changing the set-
 ting of this stop.

The above and other objects and features of
 the invention, including various novel arrange-
 35 ments and desirable constructions, will be ap-
 parent from the following description of the il-
 lustrative embodiment shown in the accompan-
 ying drawing, in which:

The figure is a side elevation of the control,
 with the expandible chamber broken away in
 section.

40 In the illustrated arrangement, a suitable base
 10 has mounted thereon a switch 12, of any de-
 sired type, shown as actuated by a plunger 14.
 The plunger 14 is engaged by a vertical part 16,
 45 having a relatively short throw, of a bellcrank
 lever having a horizontal arm 18, and fulcrumed
 on a pivot 20 carried by the base 10.

The arm 18 has an upwardly-offset portion 22
 engaged by an expandible chamber 24, deliber-
 ately constructed to have relatively little resi-
 50 lience, and containing the usual volatile expand-
 ing operating fluid. If the entire device is
 mounted at the point whose temperature is to
 control the switch, the chamber 24 may be
 55 sealed; or if there is to be a control from some
 remote point, the chamber may be connected by
 a conduit 26 with a bulb or the like at the point
 whose temperature is to control the switch 12.
 The part 24 may be made by soldering or welding

or otherwise securing together the margins of
 two disks, preferably of light-gauge metal.

A leaf spring 28 is riveted or otherwise secured
 to the end of the lever 16—18—22, to form an
 extension thereof. Springs of this character
 are readily made with substantially uniform
 10 characteristics. The end of this spring bears
 against an adjustable stop such as a setscrew
 30 threaded through a bracket 32 mounted on
 the base 10. Thus expansion of the operating
 fluid flexes the spring 28 against the stop 30, and
 the device is readily adjusted by changing the
 setting of this stop.

As the arm 18—22, plus the spring 28, forms a
 very long lever arm, the adjustment is very sen-
 sitive. This is important, as the expansion of
 the device 24 which actuates the switch is a
 15 very small amount, necessitating extremely ac-
 curate setting of the resistance against which
 it operates.

20 While one illustrative embodiment has been
 described in detail, it is not my intention to
 limit the scope of my invention to that embodi-
 ment, or otherwise than by the terms of the
 25 appended claims.

I claim:

1. A thermostatic control or the like compris-
 ing a switch, a pivoted lever having on one side
 of its pivot a part with a relatively small throw
 arranged to actuate said switch, an expandible
 30 chamber engaging said lever on the other side
 of the pivot from said part and containing an
 operating fluid and having relatively little in-
 herent resilience, a leaf spring secured to and
 35 forming an extension from the end of said lever
 on the other side of the pivot from said part,
 and an adjustable stop engaging the spring some
 distance beyond the end of the lever and against
 which the spring is flexed by expansion of said
 40 chamber by the fluid.

2. A thermostatic control or the like compris-
 ing a switch, a pivoted lever having on one side
 of its pivot a part with a relatively small throw
 arranged to actuate said switch, an expandible
 45 chamber engaging said lever on the other side
 of the pivot from said part and containing an
 operating fluid and having relatively little in-
 herent resilience, a leaf spring secured to and
 50 forming an extension from the end of said lever
 on the other side of the pivot from said part, a
 bracket adjacent the end of the spring, and an
 adjustable setscrew threaded into said bracket
 55 and engaging the spring some distance beyond
 the end of the lever and against which the spring
 is flexed by expansion of said chamber by the
 fluid.

KEMPER P. BRACE.
